UNITED STATES PATENT OFFICE.

BENJAMIN F. MAYO, OF SALEM, MASSACHUSETTS, ASSIGNOR TO THE McKAY SHOE MACHINERY COMPANY, OF PORTLAND, MAINE, AND BOSTON, MASSACHUSETTS.

DESIGN FOR A PROTECTIVE SLUG.

SPECIFICATION forming part of Design No. 30,841, dated May 23, 1899.

Application filed April 26, 1899. Serial No. 714,598. Term of patent 14 years.

To all whom it may concern:

Be it known that I, BENJAMIN F. MAYO, a citizen of the United States, residing at Salem, in the county of Essex and Commonwealth of 5 Massachusetts, have invented and produced a new and original Design for a Protective Slug, of which the following is a specification.

Figure 1 shows in end view a protective slug, representing my design; and Fig. 2 shows the 10 same in perspective looking at it in the direction of its open wings.

The leading feature of my design for a protective slug consists of an elongated body bent transversely at two points to form wings 15 united by a connecting portion, said wings being concavo-convex in shape and being spread outwardly.

The protective slug comprises an elongated

body bent transversely at two points *a b* to leave a connecting portion *c* and two wings *d e*, the said wings being concavo-convex in shape and spread apart, as represented in the drawings.

Having described my design, what I claim as new, and desire to secure by Letters Patent, is—

The design for a protective slug substantially as herein shown and described.

In testimony whereof I have signed my name to this specification in the presence of 30 two subscribing witnesses.

BENJAMIN F. MAYO.
